UNITED STATES PATENT OFFICE.

HENRY ERNST, OF CHICAGO, ILLINOIS.

HINGE.

No. 918,135.

Specification of Letters Patent.

Patented April 13, 1909.

Application filed December 9, 1908. Serial No. 466,586.

To all whom it may concern:

Be it known that I, HENRY ERNST, a citizen of the United States, residing at Chicago, in the county of Cook and State of Illinois, have invented certain new and useful Improvements in Hinges, of which the following is a specification.

This invention relates particularly to spring hinges used for hanging doors.

10. The object of the invention, generally stated, is to provide a hinge, the parts of which may be formed wholly of sheet metal stampings.

In the accompanying drawings, Figure 1 is an elevation of a hinge embodying the features of my invention, one of the leaves being represented as opened. Fig. 2 is a top plan view of the hinge with both leaves closed. Fig. 3 is a horizontal transverse section through the hinge. Fig. 4 is a perspective view of the central web or member.

The embodiment herein shown of my invention is a double-action spring hinge. The central member is an integral sheet metal stamping comprising the web 1 having at its corners horizontally extending perforated ears 2 to receive the pintles 3 of the hinge, and curved flanges 4 joining the ears at opposite vertical edges of the web 1. Prefer-

ably the upper and lower edges of the web 1 are thickened to form stiffening ribs 5. Upon the pintles 3 are mounted leaves 6, each of said leaves having a barrel 7 that incloses a coiled spring 8. Each of the leaves 6 as herein shown, has a flange or rib 9 at its upper and lower edges on each face, which flanges fit over the upper and lower ends of the central web 1, as indicated in Figs. 1 and 2.

I claim as my invention:

1. A central member for double - acting spring-hinges comprising a web having ears at its corners extending at right angles to said web, and curved flanges at the opposite vertical edges of said web joining pairs of ears. 45

2. A central member for double - acting spring - hinges comprising a web, horizontally-extending ears at the corners of said web, curved flanges connecting pairs of ears at opposite vertical edges of said web, and 50 stiffening ribs at opposite horizontal edges of said web, all of said parts being formed of an integral piece of sheet metal.

HENRY ERNST.
